UNITED STATES PATENT OFFICE.

HENRY C. EGERTON, OF RIDGEWOOD, NEW JERSEY.

GRIPPING RUBBER SHOE-HEEL.

1,352,734.

Specification of Letters Patent. Patented Sept. 14, 1920.

Application filed October 18, 1918. Serial No. 258,743.

To all whom it may concern:

- Be it known that I, HENRY C. EGERTON, a citizen of the United States, and resident of Ridgewood, county of Bergen, State of New Jersey, have made a certain new and useful Invention Relating to Gripping Rubber Shoe-Heels, of which the following is a specification taken in connection with the accompanying drawing.
- 10 This invention relates especially to gripping rubber shoe heels having wearing surfaces largely composed of resilient vulcanized rubber compositions in which are embedded and securely united gripping and strengthening elements comprising fabric or other suitable fibrous or porous material containing cured phenolic condensation cementing material, such as bakelite, condensite or redmanol varnish compositions, for instance. These elements may be conveniently cemented and secured to a stiffener or backing member of similar fabric which may form the base of the heel and facilitate its union with other shoe elements, or 25 where instead of being a separate heel the heel element is united or formed integral with a shoe sole this stiffener or backing member may extend beneath the shank and other sewed portions and be united to the rubber elements thereof. These gripping and stiffening members may advantageously comprise folded or doubled portions of canvas or other suitable fabric arranged in any desired way within the vulcanized rubber body of the heel to which they are securely cemented and united so that they have the desired gripping and wear-resisting action, and if desired metal plates or elements may be incorporated and united 35 to the heel preferably by embedding them in such fabric stiffener members to which they may be securely cemented and united by the incorporated cured phenolic condensation cementing material.
- 40 45 In the accompanying drawing showing in a somewhat diagrammatic way illustrative embodiments of this invention, Figure 1 is a perspective view partly in section showing one form of heel which may be attached to a shoe sole. Fig. 2 is a plan view showing the fabric blank which may be used for producing the same. Fig. 3 is a perspective view showing the assembled fabric members for such a heel.
- 50 55 60 65 70 75 80 85 90 95 100 105 110
- Fig. 4 is a perspective view showing another form of heel having spirally arranged gripping members. Fig. 5 is a longitudinal section thereof. Fig. 6 shows a method by which such heels may be made; and Figs. 7 to 12 are partial sectional views showing other heel constructions. As shown in Fig. 1, the heel member which may of course be a separate heel or attached to other shoe sole portions, such as 1, may comprise the body 3 of vulcanized rubber composition of any desired character preferably having such proportions of the ingredients as to be relatively resilient and given the desired toughness and wear resisting properties. If desired a backing or stiffener member 5 of canvas or other suitable heavy fabric may be used to support this heel and other canvas or woven or knit fabric of any suitable character, such as heavy army duck 4 may be united to this backing member and may be formed with suitable folds or projecting portions so as to project upward toward or to the wearing or tread surface 2 of the heel. As indicated a strip or layer 4 of such material which is preferably coated or quite thoroughly impregnated with suitable phenolic condensation cementing material, such as bakelite, varnish No. 1, and then after drying moderately heated to render it soft and pliable, may then be bent up or folded into the desired shape to form these projecting ribs or wear resisting folds such as 7, 8, 9. A convenient form of blank for this purpose is shown in Fig. 2 and a series of folds 7, 8 may be made in such impregnated fibrous material by folding the same along the dotted lines 11 and 16 preferably after cutting or stamping out a portion 14 to facilitate this folding action. This of course reduces the area of the folded blank so that it assumes the curved dotted outline 13 shown in Fig. 2, the upstanding or projecting wearing folds or ribs, such as 7, 8, being preferably formed with junction holes, such as 9, 10, at suitable intervals to facilitate the penetration of the vulcanized rubber composition which may be molded therewith and form connecting plugs of such material passing through the holes, see Figs. 1 and 3. If desired also a diagonal wearing fold or rib such as 9, may be formed conveniently by folding the blank on the dotted

diagonal lines shown in Fig. 2 so as to form a diagonal rib 9 of generally similar height, the portion 15 of the blank being thereby retracted so that this layer 4 is substantially 5 superimposed on the backing layer 5 of similar fabric which may, if desired, be coated or impregnated with such cementing material. To facilitate the union of the rubber to the fabric adjacent the same this connected fabric may advantageously in some 10 cases be formed with a frictioned or other rubber coating 6 before it is coated or impregnated with such phenolic condensation cementing material. If desired also these 15 wearing and gripping ribs or projections may be reinforced by suitable additional material preferably of a fibrous character and one or more thicknesses 35 of such material as canvas or other fabric, paper or 20 the like similarly coated or impregnated with such cementing material may be interposed between some or all of these wearing folds or ribs described.

When the fabric is folded into such position as shown in Fig. 3, which may of course 25 be conveniently effected by forcing the parts of the fabric into the recesses of a suitable mold, it may be allowed to stiffen and harden by cooling in such mold or by additional heating thereof the cementing material 30 may be at least partially cured preferably at moderate heats of 200° F. or thereabout, which may affect the desired partial curing of the cementing material to 35 stiffen and strengthen these projecting ribs and secure, if desired, the additional backing strip or layer 5 thereto without undesirably vulcanizing or affecting the rubberized coating 6 thereon. The previously 40 shaped heel body 3 of any suitable vulcanizable rubber composition may then be assembled together with this fabric stiffener and backing member in a suitable mold where the parts may be cured, vulcanized 45 and simultaneously united, if desired, by heating them to temperatures of 250° to 320° F. more or less for an hour or so which is sufficient for this purpose with the usual vulcanized rubber and cementing materials 50 of this description.

As shown in Fig. 4, a rubber heel may in some cases be advantageously formed with a spiral or more or less closed curve form of heel stiffening rib comprising one or more 55 strips or layers of fabric such as cloth, paper or other fibrous material containing and preferably quite thoroughly impregnated with such phenolic condensation cementing material. The spirally arranged layers of 60 such gripping and wearing member 20 may be interposed between the layers 17 of vulcanized rubber on the wearing heel surface 2 which may, if desired, be either a separate heel or formed integral with the shank or 65 other portions 1 of a shoe sole. A con-

venient way for forming such a rubber fabric member is shown in Fig. 6 where two layers 22, 23 of canvas or other suitable cotton or other fabric may be formed with frictioned or other rubberized coating 6 on their outer 70 surfaces and then impregnated or coated with such phenolic condensation cementing material and forced together after heat softening, if desired. In order to unite the layers 24, 25 of vulcanized rubber composition 75 of any suitable character with which these fabric members are incorporated it is desirable to form the fabric with suitable junction holes 26 and then the rubber layers or members may be applied on both sides 80 of the fabric and rolled or pressed together to cause the union of these relatively soft plastic rubber layers through the holes, such connecting plugs of rubber greatly facilitating of course the strength of union of 85 the parts. Such a composite fabric rubber strip may then be rolled up into spiral form as shown in Fig. 6 so that the convolutions 90 of fabric are suitably arranged and then after the roll of heel stock is of the desired size it may be severed along the dotted lines as by band knives so as to form pieces of the desired thickness which may be vulcanized, and if desired simultaneously united to a suitable connector and backing member, 95 such as 18, 19, of fabric, together with an interposed cushioning strip or layer 21 of similar rubber composition, if desired. These parts may be assembled in a suitable mold and forced together under pressure 100 at the desired heat to cause the curing and vulcanizing of these parts and their union into an integral heel member which is facilitated by forming the connector layer 18 with a rubberized coating 6 as indicated in 105 Fig. 5. If desired also a metal reinforcing strip or member, such as 42, of steel, copper or other suitable metal may be incorporated in the heel to give additional 110 wear resisting or gripping action and a convenient way of effecting such incorporation is to interpose the metal reinforcement or strip between two such impregnated fabric strips preferably after the metal has been coated with a cured and adherent coating of 115 bakelite metal enamel or similar phenolic condensation cementing material having special adherence to metal. A coating 43 of this character facilitates the adherence of the impregnated fabric layers to the metal 120 reinforcement when the parts are molded together as described and it is of course desirable to form junction holes 44 in the metal to cooperate with the holes 26 in the adjacent fabric as indicated in Fig. 5.

Other forms of fabric or fibrous material impregnated with such phenolic condensation cementing material to the desired extent may be united or incorporated in rubber heels to give the desired wear resisting and 130

gripping action in connection with the ground. As indicated in Fig. 7, the heel having a body 27 of vulcanized rubber composition may have suitably spaced gripping pins 5 or studs 30 formed of lengths of braided, woven or twisted cord or small rope impregnated with such dried phenolic condensation cementing material as bakelite varnish compositions and incorporated in the heel at suitable distances around its tread surface 2. These elements may be secured in position in any suitable way, as for instance, by securely cementing them to one or more of the reinforcing or backing fabric layers 4, 15 5 during the molding and heat curing operation where such fabric layers are employed in the heel. Another convenient way of forming gripping studs or members is shown in Fig. 8 in which the heel body 27 20 of vulcanized rubber may be vulcanized and united to the fabric layers 4, 5 having, if desired, a similar frictioned or rubber coating 6 thereon and folded or bent up into transverse or other gripping and wear resisting projections, as indicated. A transverse fold 45 is indicated adjacent the front part of the heel with which, if desired, a reinforcing strip or member 35 of similarly impregnated fabric may be incorporated and 25 a series of projecting studs or bosses 31 may be formed by stamping up the fabric into such form which may be easily effected with heavy knit cotton fabric, for instance, after its impregnation and drying and heat softening as previously described. The openings in such fabric may advantageously be filled with suitable fibrous or other porous material 32 containing or impregnated with dried phenolic condensation cementing material of this general character or with molding bakelite or other compositions which may be forced into these cavities while the fabric is in the mold and more or less secured in position by suitable heat and pressure which may be done at the same time that the backing fabric 5 is cemented in place and cemented to these fillings at the points 33. If desired, however, the vulcanized rubber heel body may be preliminarily 40 formed with such depressions and the fabric directly stamped into the same and the stud filling or body material forced into place and the whole cured, vulcanized and united at a single heat. Fig. 9 shows another arrangement in which the connector fabric 4 may have holes or portions 34 stamped up therein so as to accommodate gripping and wearing pins or studs 30 of cord, rope or similar fibrous material impregnated with cementing material of this character so that the whole may be cured and united to the vulcanized rubber of the heel body at the same time that it is vulcanized under suitable molding conditions.

Fig. 10 shows another arrangement in which the heel is formed with such gripping or ground engaging cavities of the golf cup type which are provided with reinforcing members or linings formed of one or more sheets or layers of fabric containing such cured phenolic condensation cementing material and preferably securely united and vulcanized to the heel body and also if desired to one or more fabric or other fibrous backing stiffening members 4, 5. 70 These cup shaped reinforcing members 36 may as indicated be formed of several layers 37, 38 of impregnated knit or other heavy cloth or fibrous material which may be stamped up into such cup shape and have 75 their edges trimmed off and then be forced into engagement with a similarly impregnated or coated connector fabric 4 so that these parts may be cemented together and permanently united. This may be effectively 80 accomplished by forming the heel body of vulcanized rubber composition 27 with suitably spaced holes and then forcing the previously shaped cup reinforcing members into these cavities by suitably flaring or 85 conical plugs on one of the mold members so that they are positively held in this position and simultaneously forced against the rubber and other elements during the heat curing treatment which transforms the bakelite or other phenolic condensation material they contain into the permanently solid and stiff form desired to make them wear 90 resistant. It is desirable to form these cup reinforcements with a relatively smooth inner surface which together with the flaring shape of these members promotes their self-clearing action and facilitates the disengagement of dirt therefrom under service conditions. Generally similar reinforcements may as indicated in Fig. 11 be conveniently formed by severing suitable lengths 39 from previously impregnated tubular woven fabric, such as cotton hose fabric which may of course have a rough 100 outer surface provided with a frictioned or other rubber coating to facilitate union with the vulcanized rubber heel composition 27, if desired. These tubular reinforcing members may, if desired, be cemented to the 105 similarly impregnated connector layer 4 so that this part of the connector forms the bottom 28 of the hollow reinforcing member or gripping cup when all the parts are cured, vulcanized and united in a suitable 110 mold. Fig. 12 shows a generally similar arrangement in which these hollow reinforcing members 39 are filled with suitable material, and if desired, one or more of such members may contain fibrous or other wear 115 resisting material 41 incorporated with the phenolic condensation cementing material of any suitable character, such as molding bakelite compositions. In this way increased wear resisting action can be secured 120 125 130

at the back or any other parts of the heel while other hollow members of this kind may be filled with plugs or portions 40 of vulcanized rubber composition generally 5 similar to the heel body composition 27 so as to have a more resilient action. It is of course understood that the wear resisting action of such members may be regulated or adjusted by controlling the proportion of 10 cured phenolic condensation cementing material they contain, since such gripping members are harder and more resistant to wear when used on relatively soft ground if they contain larger proportions of such cementing material up to fifty per cent. or so 15 of the weight of the entire member. The stiffened fabric or fibrous backing member carrying or impregnated with such phenolic condensation cementing material is highly 20 desirable for rubber composition heels, whether or not they comprise such incorporated special gripping or wear resisting members. These fabric backing layers may be so strongly and securely united to the 25 rubber sole body that they effectively prevent creeping or spreading and by properly molding the heel members this strong and relatively rigid backing member makes it possible for the heels to be accurately fitted 30 to coöperating shoe sole elements and subsequent warping is of course minimized after the heels are nailed or otherwise secured in place by any suitable means.

This application is a continuation in part 35 of my co-pending applications, Serials Nos. 237,858, filed June 3, 1918 and 256,369, filed October 1, 1918, that is, it contains subject-matter taken therefrom. This invention has 40 been described in connection with a number of illustrative embodiments, forms, proportions, elements, parts, shapes, materials, compositions, and methods of preparation, production and use, to the details of which disclosure the invention is not of course to 45 be limited, since what is claimed as new and what is desired to be secured by Letters Patent is set forth in the appended claims.

1. The rubber shoe heel comprising a 50 spiral gripping heel rib formed of a composite fabric strip impregnated with cured phenolic condensation cementing material and arranged transversely to the wearing surface of the heel and forming substantially rigid separated convolutions provided 55 with junction holes, vulcanized rubber composition forming the body of said heel and substantially surrounding and vulcanized to said heel rib and forming connecting plugs extending through said junction holes and a 60 connected fabric stiffening and backing member carrying cured phenolic condensation cementing material.

2. The rubber shoe heel comprising a gripping heel rib formed of a composite fabric 65 strip impregnated with cured phenolic con-

densing cementing material and arranged transversely to the wearing surface of the heel and provided with junction holes, vulcanized rubber composition forming the body of said heel and substantially surrounding and vulcanized to said heel rib and forming connecting plugs extending through said junction holes and a connected fabric stiffening and backing member. 70

3. The rubber shoe heel comprising a gripping heel rib formed of a fabric strip impregnated with cured phenolic condensation cementing material and arranged transversely to the wearing surface of the heel and provided with junction holes, vulcanized rubber composition forming the body of said heel and substantially surrounding and vulcanized to said heel rib and forming connecting plugs extending through said junction holes and a connected fabric back- 75 ing member. 80

4. The rubber shoe heel comprising a gripping heel rib formed of a fabric strip impregnated with cured phenolic condensation cementing material, vulcanized rubber composition forming the body of said heel and substantially surrounding and vulcanized to said heel rib and a connected fabric backing member. 90

5. The rubber shoe heel comprising a spiral gripping heel rib formed of a composite fabric strip carrying cured phenolic condensation cementing material and arranged transversely to the wearing surface of the heel and forming substantially rigid 100 separated convolutions provided with junction holes, and interposed vulcanized rubber composition forming the body of said heel and substantially surrounding and vulcanized to said heel rib and forming connecting 105 plugs extending through said junction holes.

6. The rubber shoe heel comprising a spiral heel rib formed of a fabric strip carrying cured phenolic condensation cementing material and extending adjacent to the wearing surface of the heel and forming substantially rigid separated convolutions provided with junction holes, and interposed vulcanized rubber composition forming the body of said heel and substantially surrounding and vulcanized to said heel rib and forming connecting plugs extending through said junction holes. 110

7. The rubber shoe heel comprising a spiral heel rib formed of a fabric strip carrying cured phenolic condensation cementing material and extending adjacent to the wearing surface of the heel, and interposed vulcanized rubber composition forming the body of said heel and vulcanized to 115 said heel rib. 120

8. The rubber shoe heel comprising a spiral heel rib formed of a fabric strip, and extending adjacent to the wearing surface of the heel, and interposed vulcanized rubber 130

- composition forming the body of said heel and vulcanized to said heel rib.
9. The rubber composition shoe heel having a gripping or wear resisting member comprising fabric impregnated with cured phenolic condensation cementing and stiffening material and extending transversely toward the wearing surface of the heel and provided with junction holes, a perforated 5 metallic strip reinforcement incorporated in said member, vulcanized rubber composition forming the body of said heel and substantially surrounding and vulcanized to said member and forming connecting plugs extending through said junction holes and a fabric stiffening backing member carrying cured phenolic condensation cementing material and comprising a rubberized connector layer and secured to said heel body.
10. The rubber composition shoe heel having a gripping or wear resisting member comprising fabric carrying cured phenolic condensation cementing and stiffening material and extending transversely toward the 15 wearing surface of the heel, vulcanized rubber composition forming the body of said heel and substantially surrounding and vulcanized to said member, and a fabric stiffening backing member carrying cured phenolic condensation cementing material and secured to said heel body.
11. The composition shoe heel having a gripping or wear resisting member comprising fibrous material carrying cured phenolic condensation cementing and stiffening material and extending transversely toward the wearing surface of the heel and yieldable composition forming the body of said heel and secured to said member.
12. The rubber composition shoe heel comprising embedded and connected gripping wear resisting members formed of fabric carrying cured phenolic condensation cementing material and projecting toward the 20 wearing surface of the heel and forming 25 relatively rigid separated portions, and a metallic reinforcement incorporated in said members.
13. The rubber composition shoe heel comprising an embedded and connected wear resisting member formed of fibrous material carrying cured phenolic condensation cementing material and projecting toward the wearing surface of the heel. 30
14. The composition shoe heel comprising a connected wear resisting member formed of porous material carrying cured phenolic condensation cementing material and projecting toward the wearing surface of the heel. 35
15. The rubber shoe heel comprising a spiral gripping heel rib formed of fabric strip impregnated with cured phenolic condensation cementing material and arranged transversely to the wearing surface of the 40 heel and forming separated convolutions, vulcanized rubber composition forming the body of said heel and substantially embedding and vulcanized to said heel rib and a composite fabric stiffening backing member 45 carrying cured phenolic condensation cementing and stiffening material and comprising a rubberized connector layer secured to said heel body and said backing member. 50
16. The rubber shoe heel comprising vulcanized rubber composition forming the body of said heel and a composite fibrous stiffening backing member carrying cured phenolic condensation cementing and stiffening material and comprising a rubberized connector 55 layer secured to said heel body and said backing member. 60
17. The rubber shoe heel comprising vulcanized rubber composition forming the body of said heel and a fibrous stiffening 65 backing member carrying cured phenolic condensation cementing and stiffening material and secured to said heel body. 70
